UNITED STATES PATENT OFFICE.

WILLIAM SCHAAKE, OF PITTSBURGH, PENNSYLVANIA, ASSIGNOR TO WESTINGHOUSE ELECTRIC AND MANUFACTURING COMPANY, A CORPORATION OF PENNSYLVANIA.

STRAIN CLAMP.

Application filed June 30, 1921. Serial No. 481,511.

To all whom it may concern:

Be it known that I, WILLIAM SCHAAKE, a citizen of the United States, and a resident of Pittsburgh, in the county of Allegheny and State of Pennsylvania, have invented a new and useful Improvement in Strain Clamps, of which the following is a specification.

My invention relates to conductor clamps 10 and particularly to suspension strain clamps for dead-ending conductors.

One object of my invention is to provide a device of the above indicated character that shall be simple and durable in construction, economical in manufacture and effective in operation.

Another object of my invention is to provide a suspension strain clamp that shall be easy to manipulate and that shall employ 20 standard machine bolts instead of the special J-bolts commonly employed.

Heretofore, it has been usual, in suspension strain clamps, to employ special bolts of substantially J-shape to clamp a conductor in the channel of a channeled body member. These bolts are comparatively difficult to manipulate and, unless they are removed entirely, they must be turned about their axes to move them from position over 25 the channel. This movement requires a certain clearance distance between them, thus rendering the clamp unnecessarily long. Being of special construction, the J-bolts are also more difficult to replace in case of 30 damage thereto or loss thereof.

In practicing my invention, I so substitute a plurality of transversely slidable clamping dogs or plates for the J-bolts as to permit the use of standard machine bolts. 40 The arrangement permits the structure to be compact and neat in appearance, of ready manipulation and very effective in operation.

Figure 1, of the accompanying drawings, 45 is a side elevational view of a suspension strain clamp constructed in accordance with my invention, in association with a usual dead-ending suspension insulator therefor, and

50 Fig. 2 is a view taken along the line I—I of Fig. 1.

In general, a dead-ending suspension strain device, embodying a clamp of my invention, includes an insulator 1, here shown

as of the well known cap-and-pin type, comprising a cap 2 having a clevis 3, or other means for attachment to a support (not shown), an insulating body member 4 and a pin 5. A link 6 is attached, at one end, to the outer end of the pin 5, by a pin 7 60 and is similarly attached, at its other end, to a clamp 8 by a pin 9. An arcing member or horn 10 may be secured to the clamp 8 by a clamping device 11 to direct flash-over arcs away from the insulating body member 65 4 and to thereby prevent damage thereto.

The clamp 8 is provided with a channeled portion 12 for the reception of one end 13 of a conductor 14, the main body of which may, as indicated in Fig. 1, extend in a 70 horizontal direction, with the end 13 inclined downwardly in the channel 12. Ends 15 and 16 of the channeled portion 12 are flared outwardly, the latter having an under curved portion 17 of relatively great 75 radius to prevent an acute or sharp bend in the conductor 14 and the consequent concentration of fracturing tension forces at the bend.

An elongated shelf or flange 18, at one 80 side of the channel 12, is provided with a plurality of openings for the reception of standard machine bolts 19 having nuts 20 thereon, and is also provided, at its outer edge, with a raised or semi-cylindrical portion 21, as best shown in Fig. 2. The portion 21 constitutes positioning means for a plurality of clamping dogs or plates 22 that extend transversely to the channel 12 and have portions 23 conforming to the semi-cylindrical portion 21. 85

Each clamping dog or plate 22 is of substantially arch or C-shape, with the portions 23 constituting one end thereof and a portion 24 having a groove of substantially 95 V-shape constituting the other end thereof. An elongated slot 25, in each of the plates 22, extends transversely to the conductor 14 from a position substantially at the center of the V-groove portion 24 to a position over 100 one of the bolt openings in the flange 18, so that one of the bolts 19 may extend therethrough. The portion 24 projects into the channel 12 to engage the conductor 14.

In the operative or clamping position, as 105 shown in the drawing, the bolts 19 are screwed tightly against the plates 22 to firmly wedge the V-groove portions 24

against the conductor 14 and to securely position the portion 23 on the semi-cylindrical portions 21.

By releasing the nuts 20, on the bolts 19, the clamping plates 22 may be released from clamping position on the conductors 14 and, by reason of the slots 25, may be shifted transversely with respect to the channel 12 to permit the withdrawal of the conductors.

10 The clamping plates 12 thus have simple reciprocal movements on the flange 18 between the clamping and unclamping positions thereof that facilitate manipulation of the clamp during the clamping and unclamping operations.

The parts are simple and durable in construction and, by reason of the interfitting positioning and grooved portions, are very effective in their clamping functions.

20 While I have shown and described a particular form of my invention, changes may be effected therein without departing from the spirit and scope thereof, as set forth in the appended claims.

25 I claim as my invention:

1. A conductor clamp comprising two clamping members slidably movable with respect to each other along a line normal to the conductor to receive and release the latter and means for exerting a clamping action between said members along a line at substantially right angles to said line.

2. A clamp comprising a conductor-receiving member, a clamp member for co-operation therewith, one of said members having an elongated bolt-receiving portion, and a bolt extending at substantially right angles to said portion and supported on the other member, the arrangement of parts permitting the clamp member to be moved aside to receive or remove a conductor while the bolt remains in mounted position and permitting the clamp member to be secured in operative position by the bolt.

45 3. A clamp comprising a conductor-receiving member, a clamp member for co-operation therewith, one of said members having an elongated slot, and a bolt extending through said slot and supported on the other member, the arrangement of parts permitting the clamp member to be moved aside to receive or remove a conductor while the bolt remains in mounted position and permitting the clamp member to be secured in operative position by the bolt.

50 4. A strain clamp comprising a conductor-receiving channel member having a plurality of transverse openings, a plurality of clamping plates each having an elongated

slot extending transversely to said channel and a grooved conductor-clamping portion disposed over the channel and fastening members extending through each of said slots and into each of said transverse openings.

65 5. In a strain clamp, the combination with a conductor-receiving member, of a clamp having an elongated slot and a clamping portion and a bolt extending through said slot and supported on said member, the arrangement of parts permitting said clamp to be moved aside to receive or remove a conductor while the bolt remains in mounted position and permitting said clamp to be secured in operative position by said bolt

70 6. A clamp comprising a member having a conductor-receiving portion and an opening extending transversely to said portion, a clamping member having an elongated slot extending transversely to said portion and a portion for engagement with the conductor and a fastening member in said opening and extending through said slot, the arrangement of parts permitting said plate to be moved aside to receive or remove the conductor without removing said fastening member and permitting said clamp to be secured in operative position by said fastening member.

75 7. A clamp comprising a member having a conductor-receiving channel and an opening extending transversely to said channel at one side thereof, a second member having a conductor-clamping grooved portion over said channel and an elongated slot extending transversely to the channel to a position over said opening and a fastening member disposed in said opening and said slot to clamp said members against a conductor.

80 8. A clamp comprising a member having a conductor-receiving channel and an opening extending transversely to said channel at one side thereof, said member also having a positioning portion at one side of the channel, a second member having a conductor-clamping grooved portion over said channel and an elongated slot extending transversely to the channel to a position over said opening, said second member also having a portion for co-operative engagement with said positioning portion and a fastening member disposed in said opening and said slot to clamp said members against a conductor.

85 9. In testimony whereof, I have hereunto subscribed my name this 22nd day of June 1921.

WILLIAM SCHAAKE,
